UNITED STATES PATENT OFFICE

142,335

DESIGN FOR A SHIP OR SIMILAR ARTICLE

Christoffer Hannevig, New York, N. Y.

Application July 3, 1944, Serial No. 114,291

Term of patent 7 years

(Cl. D71—1)

To all whom it may concern:

Be it known that I, Christoffer Hannevig, a subject of the King of Norway, residing at 25 West 54th Street, New York city, county and State of New York, have invented a new, original, and ornamental Design for a Ship or Similar Article, of which the following is a specification, reference being had to the accompanying drawing, forming part thereof, and in which:

Figure 1 is a side elevational view of a ship or similar article, showing my new design.

Figure 2 is a front elevational view of Figure 1. Figure 3 is an enlarged detail side elevational view of the propeller, shown by means of full lines in Figures 1 and 2.

The dominant features of my design reside in the portions shown in full lines in the drawing.

I claim:

The ornamental design for a ship or similar article, as shown and described.

CHRISTOFFER HANNEVIG.
